UNITED STATES PATENT OFFICE.

ALFRED SPEER, OF PASSAIC, NEW JERSEY.

ELECTRIC CLOCK FOR USE IN EXPOSED PLACES.

SPECIFICATION forming part of Letters Patent No. 407,945, dated July 30, 1889.

Application filed September 22, 1888. Serial No. 286,115. (No model.)

To all whom it may concern:

Be it known that I, ALFRED SPEER, of Passaic, in the county of Passaic and State of New Jersey, have invented new and useful 5 Improvements in Electric Clocks, of which the following is a specification, reference being had to the annexed drawings, forming a part thereof, in which—

Figure 1 is a front elevation of a clock constructed according to my improvement. Fig. 2 is an enlarged rear elevation of the hands and hand-propelling mechanism, showing the electric circuits and controlling devices diagrammatically; and Fig. 3 is an enlarged rear 15 elevation of the ratchet-wheel, showing the detent.

Similar letters of reference indicate corresponding parts in all the views.

The object of my invention is to construct 20 a clock with a dial of large diameter and hands of corresponding length and to provide mechanism for driving the said hands by power applied to their outer extremities, thereby allowing the hands to be moved with sufficient 25 power to overcome the resistance of the wind and of ice, snow, or sleet.

My invention consists in the combination, with one or both of the hands, of electrically-operated mechanism for advancing the hands 30 by a step-by-step movement, the electro-mechanical devices acting through pawl-and-ratchet mechanism upon pinions meshing into stationary circular racks.

The invention also consists in the combination, 35 with the pawl-and-ratchet mechanism, of a detent for preventing the ratchet-wheels from being carried forward by their own momentum after they have been moved by the pawls.

It also further consists in the combination, 40 with the electro-mechanical devices carried by the hands, of a time-measuring device—such as a pendulum or clock—arranged to control the electric current.

My improved clock is designed to be constructed on a large scale for tower-clocks, 45 parks, and public places; and, although I shall describe my invention in connection with a supporting-frame, I do not limit or 50 confine myself to this construction, as both the dial and propelling mechanism may be

arranged upon a tower or similar support. The dial is formed of the hexagonal frame E, the hexagonal frame E', and radial arms F, secured to the hexagonal frames and prolonged beyond the outer frame E' to receive the characters G, which mark the hours. The dial thus constructed is mounted upon the supporting-frame D. To the radial arms F are secured two concentric circular racks $r\ r'$, 60 the rack r having its teeth upon the outer edge and the rack r' having its teeth upon the inner edge.

In the frame-work of the dial and in the supporting-frame D is journaled the shaft s, 65 to which is secured the minute-hand A, which extends in the usual way to the figures on the dial marking the hours. Upon the same shaft s, behind the hand A, is loosely mounted the hand C, which extends to a point a little beyond the rack r' . To the back of the hand A, near the outer end thereof, is secured a base-plate H, carrying a stud s^2 , upon which is journaled the ratchet-wheel W, which is provided with roller-studs e, adapted to engage the teeth of the circular rack r .

To the base-plate H are pivoted the levers $l^2\ l^3$ of the first order, the lever l^3 being pivotally connected with a rod b^3 ; the said rod being connected with the lever l^2 by a link b^2 . To the lever l^3 is pivoted the spring-pressed pawl d, which is arranged to act upon the teeth of the ratchet-wheel W. The lever l^2 carries a spring-pressed pawl d' , which engages the ratchet-wheel W. The said levers $l^2\ l^3$ and pawls $d\ d'$ are oppositely arranged with reference to each other; so that when one of the pawls is moved forward in engagement with the teeth of the ratchet-wheel W the other will be moved back preparatory to a re-engagement with the teeth of the said wheel. The motion of the lever l^3 is limited by the stops h, secured to the base-plate H. In the back of the ratchet-wheel W are inserted studs e' , and to the base-plate H is pivoted a detent l^4 , provided with pallets c, adapted to engage the studs e' . The detent l^4 is connected by a link b^4 with one end of the lever l^2 . To the back of the minute-hand A is pivoted a lever l' of the first order, which is pivotally connected with the rod b^3 . Upon a prolongation of the hand A beyond the shaft

- s are mounted two electro-magnets M M', with armature-levers *a a'*, each having an armature of magnetic material, preferably of soft iron, arranged transversely on its lever 5 opposite the face of the poles of the magnet, and between the said electro-magnets and the shaft *s* the lever *l* of the first order is pivoted to the back of the hand A. The armature-lever *a* is connected by a rod *b* with one arm 10 of the lever *l*, and the armature-lever *a'* is connected by a rod *b* with the opposite arm of the lever. Opposite ends of the said lever *l* are connected with corresponding ends of the lever *l'* by rods *b'*. One terminal of each 15 magnet M M' is connected by a wire 3 with one pole of the battery B, and the remaining terminals are connected by wires 4 5 with contacts *p*, arranged on opposite sides of the pendulum P, the said pendulum being in 20 electrical connection with the remaining pole of the battery B, so that as the pendulum swings at the end of its excursion it makes electrical contacts, which operate the magnets M M' in alternation.
- 25 A base-plate II', attached to the back of the hour-hand C, near its outer end, carries a stud *s*³, upon which is journaled a ratchet-wheel W', provided with roller-studs *e*, as in the other case, which engage the circular rack *r'*, 30 and the back of the ratchet-wheel W' is provided with studs *e'*, which are engaged by a detent *F* in the manner shown in Fig. 3. To the base-plate II' is pivoted a lever *n*⁵ of the first order, carrying two arms *n*⁶ *n*⁷. The arm 35 *n*⁶ carries a spring-pressed pawl *x*, which engages the ratchet-wheel W', and the lever *n*⁵ carries a spring-pressed pawl *y*, which also engages the ratchet-wheel W', the pawls *x y* being arranged to alternate with each other 40 in their operation. The arm *n*⁷ is connected with the detent *F*. To the back of the hour-hand C is pivoted a lever *n*⁴ of the first order, whose opposite arms are connected by the rods *m* with the corresponding arms of the 45 lever *n*⁵.
- Upon the shaft *s*, behind the hand C, is secured a spur-wheel *p'*, which engages a pinion *p*⁴, attached to the spur-wheel *p*², the said spur-wheel being arranged to turn on the 50 stud *s*', projecting from the back of the hand C. The spur-wheel *p*² engages a pinion *p*³, turning on the stud *p*⁵ and carrying the crank *n*'. The said crank *n*' is connected by a link *n*³ with a toggle formed of the bars *n* *n*², the bar *n*² being pivotally connected with the lever *n*⁴, and the bar *n* being pivoted on the stud *q*², projecting from the back of the hand C.
- The operation of my improved clock is as 60 follows: By the swinging of the pendulum P electric connection is made with the contact-springs *p* in alternation, thus sending the electric current from the battery B through the electro-magnets M M' in alternation.
- 65 When the magnet M is energized, the armature-lever *a* is drawn forward and the lever *l* is tilted on its pivot, thus imparting motion

to the lever *l'* and, through the rod *b*³ connected therewith, to the levers *l' l'*. The pawls *d d'* carried by the said levers engage the ratchet-wheel W in alternation and cause it to rotate with an intermittent rotary motion. The engagement of the roller-studs *e* with the circular rack *r* causes the hand A to advance as the ratchet-wheel W turns. The detent *F*, by engaging the studs *e'*, prevents the said wheel W from being carried forward by its own momentum. As the hand A revolves, it carries with it the spur-wheel *p'*, which, through the medium of the pinion *p*⁴ and wheel *p*², rotates the pinion *p*³, and through it the crank *n*' attached thereto. The crank *n*' imparts motion to the toggle formed of the bars *n* *n*², and the said toggle moves the lever *n*⁴, and the latter, through the medium of the rods *m*, oscillates the lever *n*⁵, which in turn operates the pawls *x y* and the detent *F*. The ratchet-wheel W', operated by the said pawls, is thus revolved intermittently, and the engagement of the studs *e* with the said ratchet-wheel causes the hand C to be carried forward at a speed which is one-twelfth that of the hand A. The detent *F* prevents the lever W' from rotating by its own momentum. The hands A C are prevented from swinging outward away from the racks *r r'* by the rollers *g g'*, which are carried by the hands and extend partly across the back of the said racks.

Having thus described my invention, I claim as new and desire to secure by Letters Patent—

1. In a clock, the combination, with the hour and minute hands, of propelling mechanism attached to the pointing ends of the hands, substantially as specified.

2. In an electric-clock movement, the combination, with the clock hands and dial, of electrically-operated pawl-and-ratchet mechanism carried near the outer ends of the hands and tracks attached to the dial and adapted to be engaged by the hand-propelling mechanism, substantially as specified.

3. In an electric clock, the combination, with the hand A, of the magnets M M', attached to the hand A, the armature-levers *a a'*, the levers *l l'*, the levers *l' l'*, the pawls *d d'*, the ratchet-wheel W, the studs *e*, carried by the ratchet-wheel, and the toothed circular rack *r*, attached to the pawl and adapted to be engaged by the studs *e*, substantially as specified.

4. In an electric clock, the combination, with the hand A, of the magnets M M', attached to the hand A, the armature-levers *a a'*, the levers *l l'*, the levers *l' l'*, the pawls *d d'*, the ratchet-wheel W, the studs *e*, carried by the ratchet-wheel, the detent *F*, and the toothed circular rack *r*, attached to the dial and adapted to be engaged by the studs *e*, substantially as specified.

5. The combination, with the minute-hand A, provided with electro-mechanical propelling mechanism, of the spur-wheel *p'*, carried by the hand A, the hand C, the pinion *p*⁴,

spur-wheel p^2 , and pinion p^3 , carried by the hand C, the crank n' , attached to the pinion p^3 , the levers $n^4 n^5$, the toggle formed of the bars $n^4 n^5$, the connecting-rod n^8 , the pawls x y , pivotally attached to the lever n^5 , the ratchet-wheel W', the studs e' , carried by the said ratchet-wheel, and the rods m , substantially as specified.

6. The combination, with a pair of clock-hands propelled electrically from their extremities, of a time electric-circuit maker and breaker, substantially as specified.

7. The combination, with the circular racks

$r r'$, and hands A C, of the rollers $g g'$, substantially as specified.

8. The combination, with a pair of clock-hands, of electro-magnetic driving mechanism carried by one of the hands and mechanism for communicating motion from the electrically-operated hand to propelling mechanism at the extremity of the other hand, substantially as specified.
